UNITED STATES PATENT OFFICE

WILLIAM A. SCHURMANN, OF CHICAGO, ILLINOIS

DESIGN FOR A COMBINATION MIRROR AND ELECTRIC LAMP

Application filed October 17, 1930. Serial No. 37,283. Term of patent 7 years.

To all whom it may concern:

Be it known that I, WILLIAM A. SCHURMANN, a citizen of the United States, and resident of Chicago, in the county of Cook and State of Illinois, have invented a new, original, and ornamental Design for a Combination Mirror and Electric Lamp, of which the following is a specification, reference being had to the accompanying drawings, forming a part thereof.

Fig. 1 is a front elevation of said mirror and electric lamp, showing my new and ornamental design.

Fig. 2 is an edge view or side elevation of said mirror and electric lamp.

The design consists of the mirror mounted on the flat back plate shown in the drawings, with a portion of said back plate extended downwardly below the lower edge of the mirror, this extension being provided with a round opening, as shown, to expose the electric lamp bulb, supported on the back of the plate.

I claim:

The ornamental design for a combination mirror and electric lamp as shown and described.

Chicago, Illinois, October 10, 1930.

WILLIAM A. SCHURMANN.
